UNITED STATES PATENT OFFICE.

CHARLES C. LAMB, OF CHICAGO, ILLINOIS, ASSIGNOR OF ONE-HALF TO WILLARD M. McEWEN, OF CHICAGO, ILLINOIS.

GEARING FOR WASHING MACHINES.

1,403,503.

Specification of Letters Patent. Patented Jan. 17, 1922.

Application filed March 11, 1920. Serial No. 364,941.

To all whom it may concern:

Be it known that I, CHARLES C. LAMB, a citizen of the United States, residing at Chicago, in the county of Cook and State 5 of Illinois, have invented new and useful Improvements in Gearing for Washing Machines, of which the following is a specification.

This invention relates to an improved 10 form of gearing particularly adapted for washing machines of the domestic type, and consists in the matters hereinafter described and more particularly pointed out in the appended claims.

15 In the accompanying drawings—

Fig. 1 is a side view of a washing machine embodying a gearing constructed in accordance with my invention;

20 Fig. 2 is a view of one end of the machine and showing the blower connected with the pipe which discharges air into the water in the machine during the washing operation;

25 Fig. 3 is a like view and shows the blower connected with a dust collector and vacuum cleaner hose;

Fig. 4 is a fragmentary vertical sectional view taken on line 4—4 of Fig. 2, and showing the pounder mechanism of the machine;

30 Fig. 5 is a horizontal sectional view taken through the support or stand of the machine and showing the gearing directly mounted on that part;

35 Figs. 6 and 7 are vertical sectional views taken on lines 6—6 and 7—7, respectively, of Fig. 4;

Fig. 8 is a vertical sectional view taken on line 8—8 of Fig. 3 to show a detail of construction;

40 Figs. 9 and 10 are enlarged vertical sectional views taken on lines 9—9 and 10—10, respectively, of Fig. 5;

Fig. 11 is a top plan view of the clutch mechanism; and

45 Fig. 12 is a vertical sectional view taken on line 12—12 of Fig. 11;

The gearing of my invention, in the form shown in Figs. 1 to 12 inclusive, comprises a support or stand 1, preferably in the form of a table and having legs 2 and a top frame 3, there being a leg at each of the four corners of said frame. The gearing is particularly adapted for use with a washing machine having two upright containers 4, 5, one within the other and preferably circular

in shape with rounded bottom walls, as 55 shown. The container 4 is the outer tub and is mounted on the support 1 in a manner to be held stationary, as by rigidly securing on the outside of the tub 4 angle-irons 6, which seat or rest on a cross-bar 7 60 on the frame 3. The cross-bar has dowel pins 8, one for each angle-iron and entering a socket 9 therein, as shown in Fig. 8. The outer container 4 is larger than the inner one 5, and the latter is mounted to be turned 65 about a vertical axis. By having one container larger than the other, there is a space between them, as shown in Figs. 4 and 10, and the inner container 5 is perforated or 70 foraminated so that it constitutes a basket which may be used as a centrifugal wringer and thus permit the garments therein to be rinsed or wrung after the washing operation has been completed and without being required to remove them from the machine 75 for that purpose. To drain off the water from the outer and inner containers, the former is provided with an outlet pipe 10 having a faucet or cock 11 at its discharge end beyond the support 1, as shown in Fig. 80 1. The tops of the containers are open to permit access into the same, and the outer tub 4 has a removable cover or lid 12, as shown. This has handles 13 to facilitate removing and placing the cover on the 85 tub 4.

To the under side of the cross-bar 7 is secured a substantially U-shaped bracket 14, this being located substantially midway between the ends of the bar and in which is 90 rotatably mounted a vertically arranged main operating shaft 15, as clearly shown in Fig. 16. On said shaft are fixed two toothed wheels 16, 17, one above the other, as shown. The upper wheel 16 is in the form of a 95 sprocket wheel, and the lower one 17 is in the form of a beveled gear wheel. Secured between the legs 2 below the bracket 14 is a flat, horizontally arranged shelf or plate 18, upon which is mounted an electric motor 100 19, arranged with its armature shaft 20 substantially horizontal. Aligned with said armature shaft is a shaft 21, supported above the plate 18 by upright standards 22, 22, these maintaining said shaft 21 in alignment with the armature shaft, the two shafts being connected together at their opposed 105 ends by a coupling member 23, as clearly

shown in Fig. 9. Loosely mounted on the shaft 21 between the standards 22 is a worm 24 meshing with a worm wheel 25 arranged above the same and fixed on a shaft 26 5 journaled at its outer end in an upright standard 27 mounted on the shelf 18, as shown. The inner end of the shaft 26 extends to the bracket 14 and is there journaled in a cross-member 28 provided on the 10 bracket for that purpose. Loosely mounted on the shaft 26 is a beveled gear wheel 29 meshing with the beveled gear wheel 17 on the main shaft 15. Said gear wheel 29 is held from movement out of mesh with said 15 gear wheel 17 in any well known manner, as by collars (not shown). Splined on the shaft 26 is a clutch collar 30 having clutch teeth to engage complementary parts on the gear wheel 29. The collar 30 is grooved to 20 receive the arms of a shifter yoke 31 constituting a part of the clutch mechanism, to be hereinafter described, and used for moving the collar 30 into and out of clutch with said gear wheel 29 for connecting it to 25 and disconnecting it from said shaft 26.

Projecting above the support or stand 1 is an upright shaft 32 extending through the bottom walls of the inner and outer containers 4 and 5, as clearly shown in Fig. 30 10. This shaft 32 extends loosely through the cross-bar 7 and has its lower end 33 made rectangular to enter a complementary shaped socket or recess 34 in the upper end of the main shaft 15, so that the shaft 32 35 will be connected with and rotated by the shaft 15 upon the turning thereof by the motor 19. Applied over the shaft 32 are two tubes 35, 36, the outer one 35, extending through the bottom wall of the basket 5, but 40 terminating short of the bottom wall of the outer tub 4. The outer tube 35 is secured to the bottom wall of the basket 5 by a two-part boss 37 and projects above said shaft and is there rigidly secured to the 45 same, so that the shaft 32 will rotate the basket 5 and not the outer tub 4. The inner tube 36 is loosely mounted on said shaft and extends through the bottom wall of the tub 4 and rests on the cross-bar 7. Said inner 50 tube is secured to said tub by a two-part boss 38. By having the lower end of the shaft or spindle 32 removably connected with the main shaft 15, and the outer tube 35 secured to the shaft 32, the basket 5 may 55 be readily withdrawn from the outer tub 4, and the latter completely removed from the support or stand 1. This permits the containers to be removed for cleansing or repair, and also to free the stand of the 60 weight of such parts so that the stand may be readily moved about when the motor operates the blower, to be later referred to, as a vacuum cleaning element.

When the clutch collar 30 is shifted to 65 connect the gear wheel 29 with the shaft 26

and the worm 24 is connected with the shaft 21, by the clutch collar to be referred to, and the motor 19 started, the basket 5 will be rotated in one direction and at the speed required for washing purposes; the speed 70 of the motor being reduced by the provision of the worm drive in the transmission mechanism described.

To rotate the basket 5 at a greater rate of speed for rinsing or wringing, the gearing 75 includes the following parts. Secured to the inner face of one of the side members of the frame 3 is an inwardly projecting bracket 39, arranged substantially horizontal, as shown in Fig. 5, and supporting a vertically 80 arranged shaft 40, as shown in Fig. 9. To the upper end of said shaft 40 is fixed a sprocket wheel 41, over which is trained a sprocket chain 42, this in turn being trained over the sprocket wheel 16 on the 85 main shaft 15, as clearly shown in Fig. 5. To the lower end of said shaft 40 is fixed a beveled gear pinion 43 meshing with a beveled gear wheel 44 loosely mounted on the shaft 21, as shown in Fig. 9. On the 90 worm 24 is fixed a clutch collar 45 having clutch teeth to engage complementary parts on a clutch collar 46 splined on the shaft 21 between the worm 24 and the beveled gear wheel 44. The clutch collar 46 is grooved 95 to receive the yoked end of a bell crank lever 47 horizontally arranged and fulcrumed on an upright post 48 on the plate 18, as shown in Fig. 11. When the clutch collar 46 has been shifted to engage the clutch collar 45, 100 the worm 24 is connected with the shaft 21, and no power is transmitted to the gear wheel 44. On the other hand, when the clutch collar 46 has been shifted to engage said gear wheel 44, the latter is connected 105 with the shaft 21 and rotated by the motor, while the worm 24 is disconnected from said shaft, the clutch collar 30 at that time being disconnected from the gear wheel 29. The main shaft 15 is then rotated by the motor 110 through the sprocket chain 42, and the basket 5 rotated at a greater rate of speed than through the worm drive, thereby giving the basket the relatively high speed required for rinsing or wringing; in other 115 words, converting the basket from a washing element into a centrifugal wringer.

The shaft 21, as shown in Fig. 9, extends through and beyond the gear wheel 44, and is there journaled in an upright standard 120 49 on said plate 18. Fixed to the outer end of said shaft 21 is a clutch collar 50 having teeth to engage a clutch collar 51 splined on the opposed end of the shaft 52 of a blower 53 mounted on said plate 18. The 125 blower shaft 52 and the shaft 21 terminate short of each other, as shown. A spring 54 surrounds said blower shaft and tends to urge the clutch collar 51 thereon into clutch engagement with the clutch collar 50. 130

The clutch mechanism also includes a rod 55 horizontally arranged and slidably mounted in one of the standards 22, as shown in Fig. 12. The outer end of this rod 55 is pivoted at 56 to an upright hand lever 57 pivoted at its lower end on the plate 18 and carrying at its handled upper end a latch 58 to co-operate with a notched segment 59 secured to the frame 3, as shown in Fig. 3. The inner end of the rod 55 is provided with the yoke 31 for engaging the clutch collar 30. The inner arm 60 of said bell-crank lever enters an elongated horizontal slot 61 in the rod 55, as shown in Fig. 11, so that when the hand lever 57 is moved the bell-crank lever will be moved. For the clutch collar 51 there is a lever 62 pivotally mounted on an upright post 63 on the plate 18. At the outer end of this lever is a yoke 20 to engage the collar 51. The bell-crank lever has a rearwardly extending arm 64 connected by a link 65 with the inner end of the lever 62, as shown in said Fig. 11. As shown, in Fig. 3, the segment 59 has three notches 66, 67, and 68. When the lever 57 is at the first notch 66, the parts of the clutch mechanism are in the positions shown in Fig. 11. Thus, the gear wheel 44 is connected with the shaft 21, and the basket 5 30 rotated by the motor at the high rate of speed required for rinsing or wringing. By shifting the hand lever 57 to the next notch 67, the bell-crank lever 47 will be moved to withdraw the clutch member 46 out of engagement with the gear wheel 44, and, by reason of the lost motion provided by the slot 61, the spring 54 will act to force the clutch collar 51 into engagement with the clutch collar 50 and thus connect the blower 35 with said motor, the remaining parts of the gearing and basket remaining idle as the blower is rotated. Shifting the hand lever 57 to the next notch 68 will move the clutch collar 30 into engagement with the gear wheel 29 and the clutch collar 46 into engagement with the clutch collar 45, thus connecting the worm 24 with the shaft 21 to rotate the basket 5 for washing purposes. The clutch collar 51 remains in connection 40 with the one 50 so that the blower will be operated at that time to discharge air into the water in the tub 4 and aid in agitating the water to effect an efficient washing of the garments in the machine.

55 On the outside of the tub 4 is a vertically arranged pipe 69 connected with a vertical pipe section 70 in the space between the tub 4 and basket 5, as shown in Fig. 4. This pipe section 70 extends below the normal water level in the tub, and is closed at its lower end by a cap or plug 71. Above the plug the pipe section 70 is provided with a plurality of holes 72, vertically disposed and arranged to discharge air against the 60 direction of rotation of the basket. The

pipe 69 is connected with the outlet of the blower by an air hose 73.

To use the blower as part of the vacuum cleaner equipment, I removably mount on the plate 18 a dust collector 74, which may 70 be connected with the outlet of the blower by a hose 75. To the inlet end of the blower is connected a hose 76, carrying at its outer end a vacuum cleaner nozzle 77, as shown in Fig. 3. At this time the hose 73 is removed, 75 as shown in said figure.

Mounted on the upper end of the outer tube 35 is a bracket 78 having depending and diverging arms 79, 79. This bracket is secured to the under side of the cover or lid 12 and thus is held from rotation with the tube 35 and shaft 32. Located above said bracket is a horizontally arranged counter-shaft 80 having at each end an eccentric 81, about which is an eccentric strap 82 connected with a reciprocating pounder 83 below the same. Rotatably mounted on the top of the bracket 78 is a beveled gear wheel 84 meshing with a beveled gear wheel 85 fixed on the shaft 80. Each 90 pounder 83 has an upright rod 86 extending through the associated arm 79 of the bracket and connected at its upper end with the associated eccentric strap, as shown in Figs. 4 and 6. To connect and disconnect the pounder mechanism to and from the tube 35, I provide a vertically arranged, rectangular rod 87 extending through the gear wheel 84 and into a square or like recess or socket in the upper end of said tube 100 35. This rod has a head above the gear wheel and there has rotative connection with the lower end of a shift member 88 yoked between its ends to straddle the shaft 80, as shown in Fig. 7, and having a head 89 above 105 the lid 12, the member 88 extending through and above the lid for that purpose. Slidably mounted on top of the lid is a latch piece 90 adapted to be moved into a notch 91 in the member 88 when the latter has been 110 raised to that position. When so raised, the rod 87 is withdrawn from engagement with the tube 35 and thus the pounder mechanism disconnected from the motor. This is done when the basket 5 is to be rotated at a rapid rate of speed for wringing or rinsing and also when the lid 12 is removed from the tub 4. When the gear wheel 84 is connected with the tube 35, power will be transmitted from the motor to reciprocate the 115 pounders 83, as is apparent.

In the form of gearing shown, there is only a single hand operated lever of the clutch mechanism, so that the operator need only move the hand operated lever into any one of the three positions mentioned for effecting the result desired.

To facilitate lifting the tub 4, it may be provided with handles 4^a on the outside thereof. The lid 12 is formed to permit the 130

113 for the eccentrics 81 to extend above the same and also a housing 114 for the gear wheel 85.

While I have shown and described in detail a gearing embodying the features of my invention, it is to be of course understood that the details of construction and arrangement of parts shown may be variously changed and modified without departing 10 from the spirit and scope of my invention.

I claim as my invention:

1. In a gearing of the character described, the combination of a support, a main operating shaft rotatably mounted on said support, 15 a motor on said support, two toothed wheels on said shaft, a second shaft rotated by said motor, power transmitting mechanism including a worm loosely mounted on said second shaft for connecting one of said toothed 20 wheels with said motor, a clutch member for said toothed wheel, two meshing gear wheels, one loosely mounted on said second shaft, power transmitting mechanism connecting the other of said gear wheels with the other 25 of said toothed wheels, and a clutch member splined on said second shaft between the gear wheel and the worm thereon for connecting and disconnecting the gear wheel and the worm to and from said second shaft.
- 30 2. In a gearing of the character described, the combination of a support, a main operating shaft rotatably mounted on said support, a motor on said support, two toothed wheels loosely mounted on said shaft, a second shaft rotated by said motor, a worm loosely mounted on said second shaft and meshing with one of said toothed wheels, a clutch member splined on said main shaft between the toothed wheels thereon for connecting and disconnecting said toothed 35 wheels thereto, two meshing gear wheels, one loosely mounted on said second shaft, power transmitting mechanism connecting the other of said gear wheels to the other of said toothed wheels, a clutch member splined on said second shaft between the worm and the gear wheel thereon for connecting and disconnecting said gear wheel and worm to and from said second shaft, and means including 40 50 a single lever for moving said clutch members.
3. In a gearing of the character described, the combination of a support, a main operating shaft rotatably mounted on said support, 45 a motor on said support, a gear wheel and a worm gear loosely mounted on said shaft, a clutch member splined on said shaft between said gear wheel and worm gear for connecting and disconnecting the same to 55 60 and from said shaft, a second shaft rotated by said motor, a worm loosely mounted on said second shaft and meshing with said worm gear wheel, a counter-shaft, two meshing beveled gears, one loosely mounted on said second shaft and the other fixed to said 65

counter-shaft, a spur gear wheel fixed to said counter-shaft and meshing with the gear wheel on said main shaft, a clutch member splined on said second shaft between the worm and the beveled gear wheel thereon for connecting and disconnecting the same to and from said second shaft, and means including a single lever for moving said clutch members.

4. In a gearing of the character described, 75 the combination of a support, a main upright operating shaft rotatably mounted on said support, a motor on said support, power transmitting mechanism connecting said motor with said shaft, a second shaft 80 aligned with said main shaft and rotated thereby, a counter-shaft arranged above said second shaft and transverse thereto, a vertically reciprocable rod substantially parallel to said second shaft, means connecting 85 said rod with said counter-shaft for reciprocating the same upon the rotation of said counter-shaft, and means connecting said counter-shaft with said second shaft for rotating the former by the latter. 90

5. In a gearing of the character described, 95 the combination of a support, a main upright operating shaft rotatably mounted on said support, a motor on said support, power transmitting mechanism connecting 100 said motor with said shaft, a second shaft aligned with said main shaft and rotated thereby, a counter-shaft arranged above said second shaft and transverse thereto, a vertically reciprocable rod substantially parallel to said second shaft, an eccentric fixed on said counter-shaft and connected with said rod for reciprocating the same, two meshing beveled gears, one fixed on the counter-shaft and the other rotated by said second 105 shaft.

6. In a gearing of the character described, 110 the combination of a support, a main upright operating shaft rotatably mounted on said support, a motor on said support, power transmitting mechanism connecting 115 said motor with said shaft, a second shaft aligned with said main shaft and rotated thereby, a counter-shaft arranged above said second shaft and transverse thereto, a vertically reciprocable rod substantially parallel to said second shaft, an eccentric fixed on said counter-shaft and connected with said rod for reciprocating the same, two meshing beveled gears, one fixed on said 120 counter-shaft and the other rotated by said second shaft, and a clutch mechanism between said second shaft and the gear wheel thereon.

7. In a gearing of the character described, 125 the combination of a support, a main upright operating shaft rotatably mounted on said support, a motor on said support, power transmitting mechanism connecting said motor with said shaft, a second shaft 130

aligned with said main shaft and rotated thereby, a counter-shaft arranged above said second shaft and transverse thereto, a vertically reciprocable rod substantially 5 parallel to said second shaft, an eccentric fixed on said counter-shaft and connected with said rod for reciprocating the same, two meshing beveled gears, one fixed on the counter-shaft and the other rotated by said 10 second shaft, a clutch member for connecting and disconnecting said second shaft to and from the gear wheel thereon, and a latch member adapted when engaged with said clutch member to hold the same in position disconnecting said second shaft and 15 the gear wheel thereon.

8. In a gearing of the character described, the combination of a support, a main upright operating shaft rotatably mounted on 20 said support, a motor on said support, power transmitting mechanism connecting

said motor with said shaft, a second shaft aligned with said main shaft and rotated thereby, a tube on and secured to said second shaft and projecting beyond the same, 25 a bracket on said tube and held from rotation, a counter-shaft journaled in said bracket above said tube and arranged transverse thereto, two vertical rods slidably mounted in said bracket on opposite sides of 30 said tube, two eccentrics fixed on said counter-shaft and connected with said rods for reciprocating the same, two meshing gear wheels, one fixed on said counter-shaft and the other rotatably mounted on said bracket, 35 and a clutch mechanism between said second shaft and the gear wheel on said bracket.

In testimony that I claim the foregoing as my invention, I affix my signature, this 40 24th day of February, A. D. 1920.

CHARLES C. LAMB.
